United States Patent Office

Des. 212,315
Patented Sept. 24, 1968

212,315

ROTARY TOOL CADDY

William D. Taylor, Wooster, Ohio, assignor to Rubbermaid Incorporated, Wooster, Ohio, a corporation of Ohio

Filed Mar. 31, 1967, Ser. No. 6,463

Term of patent 14 years

(Cl. D87—1)

FIG. 1

FIG. 2

FIG. 3

FIG. 4

FIG. 1 is a perspective view of a rotary tool caddy embodying my new design.

FIG. 2 is a top plan view thereof.

FIG. 3 is a side elevational view thereof.

FIG. 4 is a plan sectional view taken on line 4—4 of FIG. 3.

I claim:

The ornamental design for a rotary tool caddy, as shown.
